(No Model.)

H. WALTER.
DENTAL FORCEPS.

No. 511,067.

Patented Dec. 19, 1893.

UNITED STATES PATENT OFFICE.

HARRY WALTER, OF PHILADELPHIA, PENNSYLVANIA, ASSIGNOR TO GEORGE W. TEUFEL, OF SAME PLACE.

DENTAL FORCEPS.

SPECIFICATION forming part of Letters Patent No. 511,067, dated December 19, 1893.

Application filed March 23, 1893. Serial No. 467,305. (No model.)

To all whom it may concern:

Be it known that I, HARRY WALTER, a citizen of the United States, residing in the city and county of Philadelphia, State of Pennsylvania, have invented a new and useful Improvement in Dental Forceps for Veterinary Purposes, which improvement is fully set forth in the following specification and accompanying drawings.

- 10 My invention consists of dental forceps for veterinary purposes, having a fulcrum plate connected with the axis of the jaws, said plate being formed of an arm which is secured at its inner end to the jaws of the forceps at the axis thereof, and a shoe connected with the outer end of said arm, the inner end of the arm having a bearing against the portion of the jaws in front of said axis, as will be herein-after fully set forth.
- 20 Figure 1 represents a perspective view of veterinary dental forceps embodying my invention. Fig. 2 represents a plan view of a portion thereof. Fig. 3 represents a section of a portion on line x, x , Fig. 2.
- 25 Similar letters of reference indicate corresponding parts in the several figures.

Referring to the drawings: A designates a pair of dental forceps for veterinary purposes.

B designates the axis or axial pin of the 30 jaws or beaks, and C designates an arm which is connected with said axis and extends forward between said jaws, and has fitted to its outer end, in an eye thereon, the screw stem D, to which is connected the shoe E, it being 35 seen that by screwing the stem D in proper direction, the shoe E may be set nearer to or farther from the arm C, and thus adjusted according to requirements.

The portion C' of the arm C between the 40 screw F, and the jaws or beaks of the forceps bear against the side of the portion of the forceps about or around the axis, so as to provide a firm bearing for the arm against said portion, and thus increase the durability of 45 the axial portion of said arm.

The ends of the shoe are flanged so as to prevent the same from lateral displacement from the tooth on which it is supported.

The operation is as follows: The shoe is 50 placed upon the crown or face of a proper tooth, while the jaws or beaks are presented to the tooth to be extracted, said shoe thus providing a fulcrum by which the forceps may be operated in a convenient and power-

ful manner. It will be furthermore seen, that 55 the arm or bar C passes freely between the beaks or jaws without interfering with the operation of the latter. The axis B of the jaws is hollow, and receives a screw F, by which the arm C is connected with the forceps, 60 it being evident that when said screw is removed, the arm C and parts carried by the same, are disconnected from the forceps, and the latter may be used without the fulcrum attachment, as they are left intact and unaffected by such displacement. When the arm is properly located, the screw may be applied, thus connecting the former with the forceps, it being evident that the arm may turn on the screw F as its axis, and the shoe E may 70 also turn on said arm C, thus permitting the adjustment of the forceps to the tooth to be extracted, while the shoe rests upon the face or crown of the proper tooth as a bearing.

It will be noticed that by having the arm 75 C extended in front of the jaws, the said arm with the shoe therein is not in the way of the handle in operating the device, and also that a bearing is obtained at a distance from the tooth operated on, giving thereby more freedom or ease in handling the forceps.

Having thus described my invention, what I claim as new, and desire to secure by Letters Patent, is—

1. A dental forceps consisting of pivoted 35 jaws, a forwardly projecting arm the axial pin connecting said arm with said jaws, and a shoe having a stem which is fitted in an eye in the outer end of said arm, the inner end of said arm resting against part of the forceps 90 in front of the axis thereof, substantially as described.

2. Forceps having an arm, and a fulcrum shoe with a stem on its back secured thereto, said arm projecting forwardly between the 95 beaks thereof, and having its inner end resting against part of the forceps, substantially as described.

3. A dental forceps having a hollow axial pin, an arm adjustably secured to said pin, 100 and a fulcrum shoe secured to said arm, said parts being combined substantially as described.

HARRY WALTER.
